COMBINED SALAD BOWL AND STAND

Anthony Easton, New York, N. Y.

Application February 10, 1955, Serial No. 34,446

Term of patent 14 years

(Cl. D44—10)

FIG. 1

FIG. 3

Fig. 1 is a perspective view of a combined salad bowl and stand showing my new design;

Fig. 2 is a top plan view thereof on a reduced scale with the cover portion removed; and

Fig. 3 is another perspective view of that shown in Fig. 1 with the cover and cup portion removed and in an open position.

I claim:

The ornamental design for a combined salad bowl and stand, as shown.
